DRILL PRESS CLAMP

Virgil W. Eshleman, Wichita, Kans.

Application May 6, 1946, Serial No. 667,574

1 Claim. (Cl. 77—63)

1

This invention relates to a safety device for application to drill presses, whereby the jig and workpiece can be clamped rigidly on the drill press without coming loose during the drilling operation.

A principal object of the present invention is to provide a clamping device designed for application to a drill press to hold a jig and workpiece in position, wherein there is provided a single easily manipulatable element for easily and rapidly securing the work and jig and/or releasing the same as may be desired.

One of the principal features of this safety vise is that it holds the workpiece securely. Often on a drill press the jig will come loose and start swinging, thus causing injury to the hands, face and body of the operator before the switch can be reached to cut off the power.

The vise of the present invention is secured to the drill press and at all times is ready for the operator to use. It generally comprises a clamp or collar secured to the press post or column and carrying a pair of forwardly directed shanks between which is pivotally supported an end of a press arm. Associated with the press arm and oscillatably carried by and between the shanks is a cam element with means for turning the same. The cam element when turned in one direction presses upwardly against the inner end of the arm and moves the outer end down to clamp the work onto the drill table. Reverse oscillation of the cam effects release of the arm so that the jig and work may be removed.

With these and other features in view, the invention will readily be understood from the following description with the aid of the attached drawing, which forms part of this application and in which:

Figure 1 is a perspective view, with some parts broken away, of the vise as secured on the drill press column; and

Figure 2 is a perspective view of a drill jig arm as shown.

One embodiment of this invention is illustrated in the drawing, wherein numeral 10 represents the drill press column here shown as consisting of an upright, round post which supports the drill press head structure.

The vise consists of a sleeve or band 11 which fits tightly around the column 10 and is permanently secured thereon so that it cannot be removed unless the drill press is dismantled.

Welded to this sleeve 11 is a pair of forwardly directed, parallel shanks 12, 13 which are spaced

2

apart sufficiently to permit a jig arm 14 to enter between them. Through transversely directed, mating holes 15 in said shanks 12, 13 and the jig arm 14 is inserted a pivot bolt or pin 16 which supports said jig arm between said vise shanks 12, 13. The rear ends of the shanks 12 and 13 have transversely aligning bearings 17 one only of which is illustrated, intended for supporting a cam shaft 18. The shaft 18 has a cam member 19 removably secured thereon between the shanks and at one end on the outer side of the adjacent shank, a clamping lever 20 is secured. This lever is limited in its rearward or locking swinging movement by a stud 21 on the sleeve 11. In this locked position the cam 19 abuts with its high point, or the surface on the longest radius, against the underside of the jig arm 14, thereby oscillating the jig arm to force the outer end down into clamping position. By swinging the lever 20 in opposite direction, the cam pressure is released and the jig arm 14 can be reversely removed. The jig arm is shaped with an open guide 22 for the tool.

This jig arm 14 can now be exchanged for another arm 14a, having a cylindrical aperture 22a for guiding a tool and transverse openings 16a and 17a for securing the same between the shank arms 12 and 13.

By removing the shaft 17 and the cam, a securing pin, not shown, can be inserted through the bearings 17 and the rear opening 17a, which, in association with the pivot pin 16, inserted through holes 15 and the bore 16a, will hold the arm 14a securely between the shanks.

Different size adapters may be inserted in the opening 22a, in the outer end of the arm 14a.

Any other jig arms similarly equipped may, of course, be employed for interchange with jig arm 14.

It is to be understood that the invention as herein disclosed may be varied from the details described and shown without departure from the spirit of the subjoined claim.

45 I claim:

A safety vise for use upon a drill press having an upright column and a work support, comprising a member to be secured to the column, a pair of forwardly directed spaced arms rigid with the member, a relatively long arm having one end portion disposed between the spaced arms, means for pivotally holding the elongated arm between the spaced arms, a shaft rotatably supported by the spaced arms inwardly of the pivotal mounting of the long arms, a cam carried by the shaft for

engagement with the long arm from below, an operating lever carried by the shaft, and means for limiting the throw of the lever when the high point of the cam is uppermost.
